JIB TYPE CRANE

Alexander Spoliansky, New York, N. Y., assignor
to Ingalls Iron Works Company, a corporation
of Delaware

Application September 2, 1943, Serial No. 500,907

3 Claims. (Cl. 212—56)

This invention relates to a jib type crane embodying a fixed support and a swinging support to which the jib is pivotally connected, and has for an object the provision of such a crane in which there shall be included means to control the relative angular movements of the jib and the swinging support.

A further object of my invention is to provide a jib type crane which includes a fixed support and a swinging support on which the jib is hinged to afford wider angular movement to the jib, and which shall embody gear means interposed between the jib and the fixed support to effect simultaneous controlled angular movements of the jib and the swinging supports.

Jib type cranes have heretofore been proposed in which the jib, instead of being pivoted directly to an upstanding support, was pivoted to a swinging support, which was in turn hinged to the fixed support. Such cranes have a much wider possible angular movement than where the jib is pivoted directly to the fixed support. But where such a crane is so positioned that the fixed support is not in a truly vertical position, difficulties are encountered in coordinating the angular movements of the jib and the intermediate swinging supports.

My invention contemplates a construction in which all the benefits of a multiple pivoted jib are obtained and at the same time, the jib and the swinging support move together and at proportional rates of movement. This is accomplished by mounting a segmental gear on the fixed support and a similar gear on the jib, in mesh with the gear on the fixed support, the latter being also fixed to the jib. With such an arrangement, when angular movement is imparted to the jib, the gears in mesh cause the swinging support to move in the same direction but, with gears of the same diameter, at one half the angular rate of the jib. In order to withstand the compressive forces at the bottom of the jib I provide means in addition to the gear which coact between the lower end of the jib and the fixed support.

Another feature of my invention is the provision of means for locking the jib and swinging support in fixed relation to the fixed support which feature is important in the handling of heavy loads around such places as docks and on ship board.

Apparatus embodying features of my invention is illustrated in the accompanying drawing forming a part of this application, in which

Fig. 1 is a side elevational view of a jib type

crane constructed in accordance with my invention;

Fig. 2 is a plan view of the same;

Fig. 3 is a detailed view of the bottom connection of a modified form of my invention; and

Fig. 4 is a sectional view taken along the line IV—IV of Fig. 3.

Referring to the drawing for better understanding of my invention, I show a substantially vertical fixed support 10 on which is hingedly mounted a link or swinging support 11, by means of a pin 12. A jib 13 is pivoted at its upper end to the link 11 by means of a pin 14. Mounted on the support 10 is a bracket 16 to which is secured a segmental gear 17. A similar segment 18 is secured to the upper end of a vertical member 19 of the jib 13. At the lower end of the vertical member 19 is mounted a segmental gear 21, similar to the gear 18, which meshes with a similar segment 22 mounted on the stationary support 10. A heavy bracket 23 is secured to the stationary support 10 and extends outwardly beneath the gear 21, to afford vertical and horizontal support to the jib.

As seen in Fig. 2 of the drawing, the bracket 23 has integral therewith a semicircular plate 24 having a semicircular slot 26 therein. On the lower end of the vertical member 19 of the jib 13 is a pin 27 fitting into the slot 26. The pin 27 serves as a guide means for the lower end of the jib and to take in part the horizontal thrust which would otherwise be imposed on the gears 21 and 22. Preferably a ball bearing 28 is interposed between the lower end of the vertical member 19 and the plate 24.

By reference to Fig. 2 of the drawing, I show the jib 13 in dotted position after the swinging support, or link 11, has moved 45 degrees from the full line position of Fig. 2. It will be seen that while link 11 has moved only 45 degrees, the jib 13 has moved through an angle of 90 degrees. When the link 11 has moved through an angle of 90 degrees, the jib 13 will have moved through an angle of 180 degrees. I thus obtain all the advantages of a multiple pivot with controlled relative movements between the jib and its swinging supports.

With especially heavy installations it sometimes becomes advantageous to employ the jib as a support for an overhead traveling crane. I accordingly show a diagonal brace 29 which may be detachably secured at 31 to the stationary support 10 and at 32 to the jib 13. The brace 29 has secured thereto a member 33 which may be detachably secured to the swinging link support

11, as by connection to the upper pivot pin 14. When thus applied the upper surface of the jib 13 and the link or swinging support 11, are in alignment. When so secured the rails 34 for an overhead crane 36 may be mounted on the upper surface of the jib and its swinging support.

In Fig. 3 I show a modified form of my invention in which a lower stationary bracket 36 is mounted on the vertical support 10. Pivotally mounted to the stationary support 36 is a lower swinging support 37, the pivot pin 38 for said support being, of course, in axial alignment with the pin 12. The lower end of the vertical member 19, in accordance with this modification is provided with a pin 39 which pivots the lower end of the jib to the swinging support 37. The gears 21 and 22 are secured to the lower end of the vertical member and to the stationary support 10 as already discussed in the description of Fig. 1.

In accordance with the modification just described the support 37 is designed to withstand both the vertical and horizontal loads imposed by the jib on the bottom support, and less strain is placed on the gears than is the case with the arrangement shown in Figs. 1 and 2.

From the foregoing it will be apparent that I have devised an improved jib type crane which is adapted for wide angular movement and which embodies means for controlling relative movements between the jib and its swinging support.

While I have shown my invention in but two forms, it will be obvious to those skilled in the art that it is not so limited, but is susceptible of various other changes and modifications, without departing from the spirit thereof, and I desire, therefore, that only such limitations shall be

placed thereupon as are specifically set forth in the appended claims.

What I claim is:

1. In a jib type crane, a vertical fixed support, 5 a jib, a link connecting the upper end of the jib to the fixed support, segmental gears fixedly mounted on the fixed support opposite the lower and upper ends of the jib, similar segmental gears fixedly mounted on the jib at the upper and lower ends to mesh with the first mentioned gears, and guide means coacting between the lower end of the jib and the fixed support and adapted to withstand the compressive forces at the lower end of the jib.

15 2. In a jib type crane, a vertical fixed support, a jib, a link connecting the upper end of the jib to the fixed support, segmental gears fixedly mounted on the fixed support opposite the upper and lower ends of the jib, similar segmental gears 20 fixedly mounted on the jib at the upper and lower ends to mesh with the first mentioned gears, and a link connecting the lower end of the jib to the fixed support and adapted to withstand the compressive forces at the lower end of the jib.

25 3. In a jib type crane, a vertical fixed support, a jib, a link connecting the upper end of the jib to the fixed support, segmental gears fixedly mounted on the fixed support opposite the upper and lower ends of the jib, similar segmental gears 30 fixedly mounted on the jib at the upper and lower ends to mesh with the first mentioned gears, and a diagonal brace adapted for attachment to the jib, the swinging support and 35 the fixed support to hold the jib and swinging supports against relative movement.

ALEXANDER SPOLIANSKY.
